SHOE

Benjamin Gellman, Chicago, Ill.

Application May 5, 1941, Serial No. 391,912

13 Claims. (Cl. 36—2.5)

This invention relates to shoes, and more particularly shoes of the type that are buckled in place such as, for instance, hockey shoes or other sports shoes.

It is one of the objects of the present invention to provide a hockey shoe which may be quickly and easily buckled in place and wherein the stays along the sides of the two quarters will be held neatly and snugly in position.

It is a further object of the present invention to provide a shoe of the above mentioned character with reenforcing means underlying the buckle straps and extending at approximately right angles thereto for preventing bulging of the top side stays between the straps.

It is a still further object of the present invention to provide a shoe quarter for a shoe of the above mentioned character, which quarter is so arranged as to permit ready flexing of the foot at the ankle without producing corresponding bulging.

It is a further object of the present invention to provide a shoe of the above mentioned character wherein one of the straps is provided with an enlargement or patch which serves as a reenforcement for the shoe adjacent the toes thereof and protects the toes of the wearer.

It is a still further object of the present invention to provide a shoe of the above mentioned character with an improved tongue constructed to cooperate with the side stays to prevent buckling or wrinkling of the shoe at the time of flexing of the foot at the ankle.

The attainment of the above and further objects of the present invention will be apparent from the following specification, taken in conjunction with the accompanying drawing forming a part thereof.

In the drawing:

Figure 1 is a perspective view of the front and one side of a hockey shoe embodying the principles of the present invention, certain parts of the shoe being broken away to illustrate the interior construction thereof;

Figure 2 is a top view of the shoe of Figure 1;

Figure 3 is a view of one of the side quarters of the shoe of Figure 1;

Figure 4 is a fragmentary sectional view taken along the line 4—4 of Figure 3;

Figure 5 is a fragmentary sectional view taken along the line 5—5 of Figure 3; and

Figure 6 is a side view of the tongue when folded along the longitudinal center line thereof.

In the drawing, like reference numerals indicate corresponding parts in the different figures.

The shoe 1 of the present invention is formed with the usual sole 2 and includes two similar quarters 3 and 4 stitched together, a back stay 5 stitched to both quarters, a tip 6, and a tongue 7 which merges with the tip, all formed of leather. The tongue 7 consists of a piece of leather slit longitudinally from the bottom upward about half way of its length, and the two parts on opposite sides of the slit are then spread apart and sewed by lines of stitching 8—8 to a V-shaped projection integral with the tip 6 so that the projection and tongue 7 constitute one combination tongue. The tongue is provided with the usual sheepskin lining.

The quarter 3 is formed of a leather piece 9, suitably reenforced on the inner side by canvas or reenforcing strips, and by a soft leather heel liner 10, as is usual in the art. An ankle strap 12 is sewed to the piece 9 by a line of stitching 12'. An ankle buckle strap 13 similar to the ankle strap 12 is sewed to the quarter 4. The ankle buckle strap 13 terminates in a metal clasp 14, of any desired construction, which receives the strap 12. A strap 16 having an oversized patch 17 at one end thereof is secured to the forward part of the quarter 3 by a line of stitching 18. The strap 16 cooperates with a buckle 19 at the end of a patch 20, similar to the patch 17, which is sewed to the quarter 4 in the same manner that the patch 17 is sewed to the quarter 3. The patches 17 and 20 are formed of leather and serve as protecting guards for the toes of the wearer. A top facing 22 is sewed to the piece 9 of the quarter 3, and to the corresponding piece of the quarter 4, by a line of stitching 23 which also extends through the back stay 5. The two quarters are also sewed together by a line of stitching 24 extending centrally of the shoe and covered by the back stay 5. The quarter 3 has a top side stay 28 of leather sewed thereto by lines of stitching 29—29. The top side stay extends from adjacent the bottom of the quarter, indicated at 30, to the top of the quarter, indicated at 31, as one continuous strip of leather which embraces the patch 17 and has an inwardly extending short loop or cut-out portion 33 which projects towards the sole of the shoe at approximately the ankle, or slightly below the ankle, of the wearer. Two short strips of spring steel 35—36 are secured in place between the top stay and the side piece 9 of the quarter above and below the cut-out portion 33, respectively. These pieces of spring steel are illustrated in exaggerated thickness in Figures 4 and 5, it being understood

that the actual thickness of the spring steel is appreciably less than that shown in these figures, so that the spring steel produces only a very slight bulge of the top side stay 28, or no bulge at all. The tip 6 is secured to the quarters by a line of stitching that extends upwardly from the sole 2 to the point indicated by the dotted stitching lines 40.

When the shoe is in use it is buckled to the foot of the wearer by passing the straps 12 and 16 through the buckles 14 and 18, respectively. At that time the strap 12 overlies the lower part of the spring steel 35, and the strap 16 overlies the spring steel 36. These springs are thus held flat against the foot of the wearer and thereby prevent bulging of the stays 28 between the straps. The stays 28 thus fit snugly along the contour of the foot.

The strap 12 engages the foot preferably at about the ankle. When the foot is bent at the ankle there is no outward bulging of the top side stay 28 centrally between the two buckles. Two springs 35-36 are provided in lieu of one continuous spring because one continuous long spring would prevent bending of the foot at the ankle. Ordinarily there would be a tendency for the top side stay 28 to bulge outwardly between the two springs 35-36 when the foot is flexed at the ankle. Outward bulging would take place predominantly midway between the ends of the springs 35-36 if the loop or cut-cut portion 33 were not provided. If there were no cut-out at 33 then the material (which has been cut out) would bulge outwardly. By removing this material the applicant eliminates any tendency for outward bulging of the top side stay between the buckles upon flexing of the foot.

The tongue 7 is of greater width opposite the cut-out portions 33, as indicated at 56. The projecting portion 59 is opposite the cut-out 33. As a result the top side stay overlaps the tongue along the entire length of the top side stay, including the portion of the top side stay at the cut-out portion 33.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A shoe having two similar quarters on opposite sides thereof, a strap on one of the quarters over the toe portion of the shoe, a buckle on the other quarter cooperating with the strap to secure the shoe about the toe of the wearer, a second strap and cooperating buckle on the respective quarters at the ankle portion of the shoe, separate reinforcing members stiffening the edge of each quarter beneath and extending at right angles to each strap, a top side stay on each quarter, each stay overlying both reinforcing members of its quarter and having a notch therein between the members and extending towards the sole of the shoe.

2. A shoe having two similar quarters on opposite sides thereof, a strap on one of the quarters over the toe portion of the shoe, a buckle on the other quarter cooperating with the strap to secure the shoe about the toe of the wearer, a second strap and cooperating buckle on the respective quarters at the ankle portion of the shoe, separate flat reinforcing springs stiffening the edge of each quarter beneath and extending at

right angles to each strap, a top side stay on each quarter, each stay overlying both springs of its quarter and having a notch therein between the springs and extending towards the sole of the shoe.

3. A shoe having two similar quarters on opposite sides thereof, a pair of straps on one of the quarters located respectively at the toe and at the ankle portions of the quarter, a pair of buckles on the other quarter cooperating with the straps to secure the shoe about the foot of a wearer, a side stay along the forward edge of each quarter, and separate flat springs at each side stay and located one beneath each of the straps, said springs extending substantially at right angles to the straps.

4. A shoe having two similar quarters on opposite sides thereof, a pair of straps on one of the quarters, a pair of buckles on the other quarter cooperating with the straps to secure the shoe about the foot of a wearer, a side stay along the forward edge of each quarter, said straps extending over the stays and each of said stays being at a substantial angle to the straps, the outer edge of each stay being indented towards the sole of the shoe between the straps.

5. A shoe having two similar quarters on opposite sides thereof, a pair of straps on one of the quarters located respectively at the toe and at the ankle portions of the quarter, a pair of buckles on the other quarter cooperating with the straps to secure the shoe about the foot of a wearer, a side stay along the forward edge of each quarter, said straps extending over the stays and each of said stays being at a substantial angle to the straps, the outer edge of each stay being indented towards the sole of the shoe between the straps, and separate flat springs at each side stay and located one beneath each of the straps, said springs extending substantially at right angles to the straps.

6. A shoe having two similar quarters on opposite sides thereof, a pair of straps on one of the quarters located respectively at the toe and at the ankle portions of the quarter, a pair of buckles on the other quarter cooperating with the straps to secure the shoe about the foot of a wearer, a side stay along the forward edge of each quarter, said straps extending over the stays and each of said stays being at a substantial angle to the straps, the outer edge of each stay being indented towards the sole of the shoe between the straps, the shoe having a tongue the edges of which are overlaid by the side stays, the tongue having outward projections along opposite sides thereof opposite the indentations in the side stays.

7. A shoe having two similar quarters on opposite sides thereof, a strap on one of the quarters over the toe portion of the shoe, a buckle on the other quarter cooperating with the strap to secure the shoe about the toe of the wearer, a second strap and cooperating buckle on the respective quarters at the ankle portion of the shoe, separate reinforcing members stiffening the edge of each quarter beneath and extending at right angles to each strap, a top side stay on each quarter, each stay overlying both reinforcing members of its quarter and having a notch therein between the members and extending towards the sole of the shoe, the strap at the toe portion of the shoe having an enlargement at the lower end thereof constituting a toe patch, the strap at the ankle portion extending downwardly and rearwardly along the side of the quarter towards

the heel portion of the shoe and terminating substantially at the bottom of the quarter.

8. A shoe having two similar quarters on opposite sides thereof, a strap on one of the quarters over the toe portion of the shoe, a buckle on the other quarter cooperating with the strap to secure the shoe about the toe of the wearer, a second strap and cooperating buckle on the respective quarters at the ankle portion of the shoe, separate reenforcing members stiffening the edge of each quarter beneath and extending at right angles to each strap, a top side stay on each quarter, each stay overlying both reenforcing members of its quarter and having a notch therein between the members and extending towards the sole of the shoe, the shoe having a tongue between the quarters which tongue is overlaid by the side stays and has outwardly extending projections along the opposite sides thereof at the notches in the side stays, said projections extending beneath the side stays at the notches.

9. A shoe having two similar quarters on opposite sides thereof, a strap on one of the quarters over the toe portion of the shoe, a buckle on the other quarter cooperating with the strap to secure the shoe about the toe of the wearer, a second strap and cooperating buckle on the respective quarters at the ankle portion of the shoe, separate reenforcing members stiffening the edge of each quarter beneath and extending at right angles to each strap, a top side stay on each quarter, each stay overlying both reenforcing members of its quarter and having a notch therein between the members and extending towards the sole of the shoe, the two quarters terminating at the sole of the shoe and being spaced from one another at the toe part of the sole of the shoe, a tongue extending to the sole of the shoe between the quarters and joining the foremost lower parts of the quarters, said tongue being overlaid by the side stays and having outwardly extending projections along the opposite sides thereof at the notches in the side stays, which projections extend beneath the side stays at the notches.

10. A shoe having two similar quarters on opposite sides thereof, a pair of straps on one of the quarters located respectively adjacent the toe and ankle portions of the quarter, a pair of buckles on the other quarter cooperating with the straps to secure the shoe about the foot of a wearer, and separate flat springs secured along the forward

edge of each quarter and located one beneath each strap when the straps are in engagement with the buckles, said springs extending substantially at right angles to the straps.

5 11. A shoe having two similar quarters on opposite sides thereof, a pair of straps on one of the quarters, a pair of buckles on the other quarter cooperating with the straps to secure the shoe about the foot of a wearer, a side stay along the 10 forward edge of each quarter, said straps extending over the stays and each of said stays being at a substantial angle to the straps, the outer edge of each stay being indented towards the sole of the shoe between the straps, the shoe having a 15 tongue between the quarters which tongue is overlaid by the side stays and has outwardly extending projections on the opposite sides thereof at the indentations in the side stays, said projections extending beneath the side stays at the indentations.

20 12. A shoe having two similar quarters on opposite sides thereof, a strap on one of the quarters over the toe portion of the shoe, a buckle on the other quarter cooperating with the strap to secure the shoe about the toe of the wearer, a second 25 strap and cooperating buckle on the respective quarters at the angle portion of the shoe, separate reenforcing members stiffening the edge of each quarter beneath and extending at right angles to each strap, the forward edge of each quarter having a notch therein between the reenforcing members, said notch extending towards the sole of the shoe.

30 13. A shoe having two similar quarters on opposite sides thereof, a strap on one of the quarters over the toe portion of the shoe, a buckle on the other quarter cooperating with the strap to secure the shoe about the toe of the wearer, a second 35 strap and cooperating buckle on the respective quarters at the ankle portion of the shoe, separate reenforcing members stiffening the edge of each quarter beneath and extending at right angles to each strap, the forward edge of each quarter having a notch therein between the reenforcing members, said notch extending towards the sole of the shoe, the shoe having a tongue 40 between and overlaid by the two quarters, said tongue having projections on opposite sides thereof at the notches and extending beneath the quarters at the notches.

BENJAMIN GELLMAN.
